(57) **CLAIM**

The ornamental design for a twin dual port network device, substantially as shown and described.

DESCRIPTION

FIG. 1 is a perspective view of a twin dual port network device, showing our new design;

FIG. 2 is a top view thereof;

FIG. 3 is a bottom view thereof;

FIG. 4 is a right side view thereof;

FIG. 5 is a left side view thereof;

FIG. 6 is a rear view thereof; and

(Continued)

FIG. 7 is a front view thereof.

The broken lines depict portions of the twin dual port network device, which form no part of the claimed design.

1 Claim, 5 Drawing Sheets
